COMBINED ICE CRUSHER AND DRINK MIXER APPLIANCE

Norman A. Steinkamp, Chicago Heights, Ill., assignor to
Sunbeam Corporation, Chicago, Ill.

Filed Jan. 11, 1971, Ser. No. 105,769

Term of patent 14 years

Int. Cl. D7—04

U.S. Cl. D89—1 D

FIG. 1 is a perspective view of a combined ice crusher and drink mixer appliance embodying my new design; FIG. 2 is a side elevational view thereof;

FIG. 3 is a top plan view thereof;

FIG. 4 is a rear elevational view thereof;

FIG. 5 is a side elevational view of the side opposite that shown in FIG. 2;

FIG. 6 is a fragmentary sectional view along line 6-6 of FIG. 4; and

FIG. 7 is a fragmentary sectional view along line 7-7 of FIG. 4.

I claim:

The ornamental design for a combined ice crusher and drink mixer appliance, as shown.
